CLAIM

(22) Filed: **Aug. 20, 2024**

The ornamental design for module for circular seed manifold, as shown and described.

Related U.S. Application Data

(62) Division of application No. 18/410,518, filed on Jan. 11, 2024.

DESCRIPTION

(51) **LOC (15) Cl.** **15-03**

FIG. 1 is a perspective view of a seed tube module according to the present invention, and which comprise a portion or segment of a circular seed manifold.

(52) **U.S. Cl.**

FIG. 2 is another perspective view of the module shown in FIG. 1.

USPC **D15/28**; D15/13
CPC **A01C 7/082** (2013.01); **A01C 7/206**

FIG. 3 is a top plan view of the module shown in FIG. 1.

(2013.01)

FIG. 4 is a bottom plan view of the module shown in FIG. 1.

(58) **Field of Classification Search**

FIG. 5 is a side elevation view of the module shown in FIG. 1.

USPC D15/13, 10, 28-33; 222/410; D8/2
CPC G01F 11/24; B65G 65/4836; B65G 65/48;
B65G 53/40; A01C 7/082; A01C 7/081;
A01C 7/084; A01C 7/088; A01C 15/06

FIG. 6 is a side elevation view of the module from the

See application file for complete search history.

opposite side of FIG. 5.

(56) **References Cited**

FIG. 7 is a front elevation view of the module shown in FIG. 1; and,

U.S. PATENT DOCUMENTS

FIG. 8 is a rear elevation view of the module shown in FIG. 1.

239/650

Structure, environment, and/or boundaries shown in broken lines form(s) no part of the claimed design.

4,815,414 A 3/1989 Duffy et al.

Some aspects of the module for circular seed manifold are shown with symbolic breaks in dimension: e.g., height, width. The appearance of any portion of the module for circular seed manifold between the break lines forms no part of the claimed design.
